Primary Examiner — Cynthia Ramirez*Assistant Examiner* — Llorellys Martinez-Rivera(74) *Attorney, Agent, or Firm* — Ware, Fressola, Maguire & Barber LLP(57) **CLAIM**

The ornamental design for a corner extrusion, as shown and described.

DESCRIPTION

FIG. 1 is a top perspective view of a corner extrusion showing our new design;

FIG. 2 is a left side elevational view thereof;

FIG. 3 is a top plan view thereof;

FIG. 4 is a front elevational view thereof, the rear elevational view being a mirror image thereof; and,

FIG. 5 is a bottom plan view thereof.

The corner extrusion is shown with a symbolic break in its length. The appearance of any portion of the corner extrusion between the jagged break lines forms no part of the claimed design.
